CLAIM

The ornamental design for the surface pattern for firearms, as shown and described.

DESCRIPTION

FIG. 1 is a left side elevation view of a surface pattern for firearms in accordance with a preferred embodiment of my design;

FIG. 2 is a right side elevation view of the firearm surfaces of FIG. 1;;

FIG. 3 is a front side elevation view of the firearm surfaces of FIG. 1;

FIG. 4 is a rear side elevation view of the firearm surfaces of FIG. 1;

FIG. 5 is a top view of the firearm surfaces of FIG. 1; and,

FIG. 6 is a bottom view of the firearm surfaces of FIG. 1.

The dashed lines shown in the figures represent environmental subject matter and form no part of the claimed design.
